HANDLE FOR TEA KETTLES OR THE LIKE

Austin H. Munson, Mount Prospect, Ill., assignor to Ekco Products Company, Chicago, Ill., a corporation of Delaware

Filed Sept. 11, 1962, Ser. No. 71,649

Term of patent 14 years

(Cl. D44—29)

FIG. 1 is a side view of a handle for tea kettles or the like showing my new design.

FIG. 2 is a reverse side view thereof.

FIG. 3 is a front end elevation thereof.

FIG. 4 is a rear end elevation thereof.

FIG. 5 is a top plan view thereof.

FIG. 6 is a bottom plan view thereof.

The stippling on the drawing indicates an area of contrasting surface texture.

I claim:

The ornamental design for a handle for tea kettles or the like, substantially as shown and described.
